(57) **CLAIM**

I claim the ornamental design for a combined butter stick platform and corn cob rest, as shown and described.

DESCRIPTION

FIG. 1 is a perspective view of a combined butter stick platform and corn cob rest.

FIG. 2 is a front view of the combination platform and rest, with the back view being a mirror image thereof.

FIG. 3 is a right side view of the combination platform and rest, with the left side view being a mirror image thereof.

FIG. 4 is a top view of the combination platform and rest.

FIG. 5 is a bottom view of the combination platform and rest.

FIG. 6 is a perspective view of an alternative embodiment of a combined butter stick platform and corn cob rest.

FIG. 7 is a front view of the alternative combination platform and rest, with the back view being a mirror image thereof.

FIG. 8 is a right side view of the alternative combination platform and rest, with the left side view being a mirror image thereof.

FIG. 9 is a top view of the alternative combination platform and rest; and,

FIG. 10 is a bottom view of the alternative combination platform and rest.

The broken lines shown in the drawings show portions of the combined butter stick platform and corn cob rest that form no part of the claimed design.
